UNITED STATES PATENT OFFICE

2,621,353

MOP HOLDER HAVING SCREW-OPERATED CLAMPING PLATE

John F. Bagley, Jr., South Hadley, Mass., assignor to Stanley Home Products, Inc., Westfield, Mass., a corporation of Massachusetts

Application April 14, 1950, Serial No. 155,888

1 Claim. (Cl. 15—153)

1

This invention relates to improvements in connectors and is directed more particularly to improvements in devices for connecting handles and brushes, mops, and the like.

This application is an improvement in the mop clamp of application, Ser. No. 82,256, filed March 18, 1949, which matured as Patent Number 2,550,397, April 24, 1951.

The principal object of the invention is the provision of a connector which is simple in form and efficient in operation, wherefore a handle and mop or the like may be readily and easily connected and disconnected.

I accomplish the above object by means of such structure and relative arrangement of parts thereof, as will fully appear by a perusal of the description below and by various specific features which will be hereinafter set forth.

To the above cited and other ends and with the foregoing and various other novel features and advantages and other objects of my invention as will become more readily apparent as the description proceeds, my invention consists in certain novel features of construction and in the combination and arrangement of parts as will be hereinafter more particularly pointed in the claim hereunto annexed and more fully described and referred to in connection with the accompanying drawings wherein:

Fig. 1 is a plan view of a connector embodying the novel features of the invention;

Fig. 2 is a side elevational view of the connector shown in Fig. 1; and

Fig. 3 is a sectional view on the line 3—3 of Fig. 2.

Referring more to the drawings in detail, the invention will be fully described.

A body 2 is provided which will preferably be formed from sheet metal by any well known metal working method.

A rear end portion 4 of the body may be of any form or shape for attachment to a handle so that the handle may be connected by means of the device to a mop, broom or the like.

The body has an intermediate portion 6 and a forward portion 8 which are generally channel shape in transverse cross-section. The forward section inclines upwardly as shown in Fig. 2.

The intermediate portion 6 and forward portion 8 being channel shape in cross-section, there are longitudinal lips 10 and 12 at opposite sides thereof with vertical shoulders 14 inwardly from the end of the forward portion.

A clamp plate 16 has a forward portion 18 and a rear declining portion 20.

2

A screw 22 of any desired form extends upwardly from the body and through a slot 24 in the plate 16.

A retainer 26 in the form of a T is struck up from the body and the rear end of the plate 16 is provided with a slot 28 and arranged so that the transverse part 30 of the retainer is disposed over the said rear end of the plate.

The longitudinal side edges of the plate 16 preferably curve downwardly at 32 and the forward transverse end 34 of the plate curves downwardly.

A spring 36 surrounds the screw 22 and a wing nut 38 is in threaded engagement with the screw.

The spring 36 urges the plate upwardly against the wing nut and the retainer and slot at the end of the plate prevent displacement of said plate while allowing up and down movements thereof.

The forward end of the body, forward end 20 of the plate and shoulders, disposed as they are, provide a transverse channel 40 for receiving a member of a mop, brush, or the like. Said member is clamped in the channel by forcing the plate downwardly by the member 38 against the action of spring 36.

The channel shape arrangement of the forward portions of the plate and body providing the lips 32 and 12 provide spaced cooperating means for securely gripping a part of a mop, brush, or the like therebetween.

The invention may be embodied in other specific forms without departing from the essential characteristics thereof. Hence, the present embodiments are therefore to be considered in all respects merely as being illustrative and not as being restrictive, the scope of the invention being indicated by the appended claim rather than by the foregoing description, and all modifications and variations as fall within the meaning and purview and range of equivalency of the appended claim are therefore intended to be embraced therein.

What it is desired to claim and secure by Letters Patent of the United States is:

45 A connector for connecting a handle to a mop comprising in combination, a body having a rear end for attachment to the handle and an upwardly inclined forward end for engagement with the mop, a clamp plate having a rear declining bifurcated end defining a slot and a forward mop engaging end, a screw extending upwardly from said body and through a central opening in said clamp plate, a spring disposed around said screw between said body and clamp plate for urging 50 said clamp plate upwardly, a nut threadedly en- 55

gageable with said screw and disposed above said clamp plate for resisting the upward thrust of said spring, a T-shaped retainer extending upwardly from said body having a transverse free upper end portion, said retainer being receivable in the slot in said clamp plate with the transverse end portion of said retainer overlying and bearing upon said clamp plate, spaced side walls on opposite sides of said body and clamp plate in opposed relationship and cooperating to provide gripping means for securing the mop therebetween.
